PUMP

Filed March 16, 1923

Inventor

Harry Jackson

By his Attorney

Torrence V. Decker

UNITED STATES PATENT OFFICE.

HARRY JACKSON, OF BROOKLYN, NEW YORK.

PUMP.

Application filed March 16, 1923. Serial No. 625,483.

To all whom it may concern:

Be it known that I, HARRY JACKSON, a citizen of the United States, and a resident of Brooklyn, in the county of Kings and 5 State of New York, have invented certain new and useful Improvements in Pumps, of which the following is a specification.

My invention relates to a pump and aims to provide a device of this character particularly adapted to be employed in connection with the dispensing of lubricating oils and similar heavy fluids although the same 10 is not necessarily limited to this particular use.

It is an object of the present invention to provide a pump particularly intended for the dispensing of lubricating oils which pump is adapted to be associated with a receptacle within which the fluid is stored, the 15 said pump being of a type which is manually and intermittently operated and by means of which a predetermined amount of fluid will be dispensed each time it is actuated.

A further object of my invention resides 20 in the construction of a device of the character stated in which the parts may be adjusted to work in such a manner that exactly the proper quantity of fluid will be dispensed, these parts being susceptible to adjustment to compensate for wear as well as 25 for inequalities in the manufacture of the device.

A still further object of my present invention is that of constructing a pump particularly 30 intended for operation by means of a crank and in which this crank will be connected with the operating mechanism thereof in such a manner that the greatest amount of leverage will be obtained so that a predetermined amount of fluid may be dispensed 35 with a minimum of effort, on the part of the operator, and within a shorter interval of time than has heretofore been possible in this type of pump.

Another object of my invention is that of arranging the pump mechanism in such a manner that any tendency of the parts thereof to bind during the actuation of the pump will be entirely eliminated so that the mechanism 40 will always operate in a positive manner and with freedom from mechanical complications.

Still another object of my invention is that of constructing a pump having a nozzle 45 or delivery spout which will be of such a

type as to reduce to a minimum the amount of after-drip therefrom.

My invention also aims to provide a pump which may readily be associated with the receptacle from which the fluid is to be drawn 50 and in which a structure will be provided serving to effect a return to the receptacle of any of the fluid which may be spilled while operating the pump mechanism.

With these and further objects in mind 55 reference is had to the attached sheet of drawings as illustrating one practical embodiment of my invention and it will be seen in these drawings that:

Fig. 1 is a sectional side view of a pump 70 embodying my improved construction.

Fig. 2 is a fragmentary transverse sectional view of a certain part of the mechanism thereof and

Fig. 3 is a plan view taken along the lines 75 3—3 and in the direction of the arrows indicated in Figure 1.

As is customary in pumps of this general character I provide a casing which is identified by the reference numeral 5 and which 80 is connected at its lower end with a feed pipe 6. This casing provides a cylinder within which there is slidably mounted a piston 7, the return of fluid from within the casing into the pipe 6 being prevented by 85 any suitable type of valve such as a ball 8 cooperating with a proper seat formed at the junction of the pipe with the casing.

However, contrary to the conventional 90 construction it will be noted that the inner face of the casing provides the cylinder aforementioned and the piston and casing are preferably formed of the same metal, or metals having the same co-efficiency of expansion so that any danger of leakage or 95 binding occurring due to temperature changes, is avoided. Also, the piston is formed with openings 9 the flow of fluid through which is normally prevented by 100 means of suitable valves such as balls 10 and these openings and valves are more than two in number and are distributed at points in the piston equally spaced from each other and from a post 11 which extends upwardly 105 at a point central thereof. I have found that by this construction, which is utilized in lieu of a single or double valve carried by the piston, that the strains on the same are evenly distributed and thus the tendency 110 of this member to bind against one portion

of the cylinder face is prevented and consequently uneven wear is also precluded.

Now with a view of moving the piston within the cylinder it will be noted that I 5 employ a pair of links 12 which have one of their ends pivotally connected with the post 11 while their opposite ends are similarly secured to the ends of a pair of spaced arms 13. It is to be here noted that the 10 links 12 are preferably of a greater length than the arms 13 and these latter are secured to a shaft 14 extending transversely of a housing 15 which latter is mounted above the casing 5. Attached to the shaft at 15 a point beyond said housing is a crank 16 of any desirable type by means of which the shaft may be oscillated.

Thus it will be obvious that in order to effect a movement of the piston 7 an operator 20 will only find it necessary to move the crank 16 through a certain arc and the crank is so disposed that this arcuate movement occurs in a plane and direction in which the operator is most readily capable 25 of moving the same so that this operation of the parts is effected in the easiest possible manner, it being further noted, in this connection, that due to the fact that the arms 13 are of a shorter length than the links 12, 30 an operator gains the benefit of the best possible leverage.

Now with a view of assuring an even flow during all stages of the piston's movement it will be seen that the base 17 of the housing 15 is of a slightly larger size than the casing 5 so that an enlarged chamber 18 is formed at this point which obviously prevents any back pressure as the piston moves towards the end of the casing. Furthermore, 35 the housing 15 acts in the nature of a pressure chamber, it being seen that the nozzle 19 has its inner end in communication with the interior of the housing and in a plane adjacent the plane occupied by the shaft 14 whereby the fluid in its passage through the pump, casing and nozzle will cause the parts of the mechanism to remain properly lubricated. In order to properly regulate the working stroke of the piston 7 40 to insure the flow of a predetermined amount of fluid from the nozzle 19 and, also to provide a guide member for the said piston, it will be seen that I attach a rod 20 to the post 11 and this rod projects into a tubular 45 extension 21 forming a part of the housing 15. Adjacent the upper end of the extension there is mounted a stop member, which in the present embodiment of the invention embraces a screw-threaded lug 22 which is adjustable with respect to the extended portion 50 of the housing and which may be retained against movement by means of a lock nut. Thus the working stroke of the piston is limited at all times by contact being effected 55 between the rod 20 and the stop member

and the piston is also guided in its movements incident to the slidable engagement between the rod and extension within which it is projected, it being obvious that by means of this construction any tendency of the parts to bind is avoided and that the piston stroke may at all times be adjusted to insure of the discharge of a proper quantity of fluid from the pump upon the mechanism of the latter being operated. Also 70 it is to be noted that any binding tendency of the piston is further prevented by the disposition of the valves 10, as aforesaid, and by the use of the pair of links 12 disposed one to each side of the post 11. 80

It will be appreciated in actuating the pump that the operator simply grasps the crank 16 and swings the same in one direction until the piston reaches its limit of movement. During this operation the fluid within the casing and below the piston will be forced through the openings 9 of the latter and past the valves 10 thereof to occupy a position above the piston. Upon the operator reversing the movement of the crank 16, the valves 10 will be seated and the fluid above the piston will be forced upwardly and be discharged from the nozzle 14, which discharge will continue in the form of an even flow incident to the provision of the housing 15 providing the pressure chamber and furthermore due to the fact that no back pressure can possibly occur incident to the enlarged space 18 provided by the base 17 of the said housing. 95 This discharge of fluid from the nozzle will continue until the rod 20 engages the stop member upon which occurrence, the flow will cease without any material after-drip incident to the fact that this is prevented by 100 preferably providing a short length of tube 23 within the outer end of the nozzle and the inner end of which tube forms a baffle 24. During the aforescribed movement of the piston 7 the valve 8 will obviously be unseated and the space below the said piston will be filled with fluid but upon the rod engaging the stop the valve 8 will immediately close so that upon the piston being 105 again returned to its normal position the major portion of this fluid will lie at a point above the piston and this operation 110 may obviously be repeated as often as it is desired. 115

With a view of applying the pump to the receptacle I prefer to utilize a metallic bung 120 which is slidably mounted upon the tube 6 and may be secured in any desired position by a set screw 26. Thus a single length of pipe may be utilized and the inner end of the same may be inserted into the receptacle 27 to a point at which it engages the lower face thereof and subsequent to this operation the bung 25 may be screwed 125 into place, after which the same is tightened 130

by the use of the set screw 26. This bung carries an outwardly extending tube 28 to the outer end of which there is secured a drip pan 29 having a central opening communicating with the bore of the said tube which in turn communicates with the bore of the bung. The pan aforementioned normally serves as a platform upon which the fluid receiving receptacle is positioned and it is obvious that in the event of any of the fluid being spilled from the latter this fluid will be returned through the opening in the pan, bore of the tube and to the receptacle between the opposed faces of the bung and pipe.

Thus all of the objects of this invention are accomplished and it will be appreciated that numerous modifications of structure may readily be resorted to without in the slightest departing from the spirit of the invention as defined by my claims which are:

1. A pump including a piston, a pair of links having one of their ends connected to said piston, a crank having a swinging movement of less than 360° connected with the opposite ends of said links and a casing enclosing said piston, links and crank.

2. A pump including a casing, a piston within the same, a post secured to said pis-

ton, links having their inner ends movably connected with said post and disposed upon opposite sides thereof, a shaft extending transversely of said casing, a pair of spaced arms connected with said shaft and having their ends in turn connected with the outer ends of said links, a rod secured to said post and extending between said links and arms, and means adapted to be engaged by said rod and acting as a stop for the same.

3. A pump including a casing, a nozzle connected with said casing and a tube disposed within the outer end of said nozzle and providing a baffle within the same.

4. A pump, including a casing formed with intake and outlet openings, a shaft extending transversely of said casing and to one side of the axis thereof, a piston movable within said casing, a rod secured to said piston, guiding means forming a part of said casing and cooperating with said rod, a pair of crank arms secured to said shaft and extending one to each side of said rod, a pair of links having their upper ends attached to said crank arms, their lower ends being rockingly secured to said piston.

Signed at New York, in the county of New York and State of New York, this 15th day of March, A. D. 1923.

HARRY JACKSON.
